(57) **CLAIM**

The ornamental design for a footwear insert, as shown and described.

DESCRIPTION

FIG. 1 is a top plan view of the footwear insert showing my new design, the bottom being a mirror image;

FIG. 2 is a left side elevation view thereof;

FIG. 3 is an isometric view thereof;

FIG. 4 is an isometric view thereof; and,

FIG. 5 is an isometric view of an insole for the opposite foot.

The broken line showing of footwear in FIGS. 1-4 is for illustrative purposes only and forms no part of the claimed design.
